UNITED STATES PATENT OFFICE.

TOM WILLIAMS, OF MARYSVILLE, KANSAS.

MUSIC-LEAF TURNER.

1,265,568.

Specification of Letters Patent.

Patented May 7, 1918.

Application filed September 12, 1916. Serial No. 119,700.

To all whom it may concern:

Be it known that I, TOM WILLIAMS, a citizen of the United States, residing at Marysville, in the county of Marshall and State of Kansas, have invented certain new and useful Improvements in Music-Leaf Turners, of which the following is a specification.

This invention relates to music leaf turners, and as the primary object, contemplates the provision of a device that can be readily associated with a foldable music rack and one whereby the sheets of music may be readily and expeditiously turned by the musician while playing his musical instrument.

It is another object of this invention to provide a plurality of movable leaf holding arms with which coöperate a plurality of manually operable leaf turning arms, the latter being operable by suitable foot operating mechanism mounted on a conventional form of music rack.

It is a more specific object of this invention to provide means for adjustably mounting both the leaf turning and holding arms on a support; to provide movable catch means for automatically engaging and turning the arms; to provide resilient means for controlling the operating means for the leaf turning arms; to efficiently mount a cable about the drum for actuating purposes and to provide a portion of the support with a cam edge for facilitating the operation of the arms as well as the release of them.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

In the drawings:—

Figure 1 is a front elevation of my invention.

Fig. 2 is a side elevation thereof.

Fig. 3 is a transverse section taken through the support tube and looking down toward the drum.

Fig. 4 is a bottom plan of the drum.

Fig. 5 is a transverse section taken through the cylindrical supporting tube showing the means for holding the arm retaining bands in position.

60

Fig. 6 is an elevational detail.

Referring more particularly to the drawings in which similar reference numerals designate like and corresponding parts throughout the various views, I have illustrated a conventional form of music rack with which it is desirable to associate my invention for the purpose of gaining a thorough understanding thereof. At this point it may be understood however, that the invention can as well be associated with a piano or of various types of supports neither of which form a material part of this invention. The support in the present instance consists of a telescopic standard composed of sections 1 and 2 the latter being adjustable within and with respect to the former in any desirable manner. A plurality of legs 3 are pivoted adjacent the upper edge of the section 1 while braces 4

65

are pivotally connected from points intermediate the ends of the legs 3 and the lower end of the section 1 as illustrated to advantage in the drawings. The usual rectangular support 5 is connected to the angularly bent end of the section 2 by a suitable bracket 6. Supporting brackets 7 are connected to the upper and lower edges of the support 5 at points substantially intermediate the ends thereof and extend from the outer face of the support and in parallel relation with each other while another bracket 8 is connected adjacent the lower edge of the support 5 and extends in close spaced relation with the lower bracket 7 for 95 a purpose to be hereinafter described. A cylindrical tube 9 has stubs 10 projecting from the respective ends and journaled in the arms 7. Corrugated bands 11 and 12 are arranged about the tube 9 and have their 100 respective ends flanged as at 13 and removably engaged by tapering slides 14. The slides 14 serve to adjustably secure the bands on the tube while the bands in turn serve to pivotally connect the angularly bent ends of the leaf holding arms 15 and the angularly bent ends of the leaf turning arms 16 to the tube. The outer ends of the holding arms 15 are bent upon themselves and provide spring clips 17 each adapted for en-

gagement with a sheet of music as illustrated to advantage in Fig. 1, while the arms 16 are arranged behind a sheet of music and also bent adjacent their inner ends to provide projections 18 as shown in Fig. 1.

In order to actuate the leaf turning arms I have rotatably mounted a drum 19 between the lower bracket 7 and the bracket 8, said drum being eccentrically mounted with respect to the mounting of the tube. Catches 20 and 21 extend laterally from diametrically opposite points on the upper periphery of the drum and at times engage projections 18 on the leaf turning arms 16. This engagement is due to the arrangement of the projections which are positioned below the plane of the arms 16 and within the path of movement of the catches 20 and 21. Incidentally a portion of the lower bracket 7 is provided with a cam surface 22 adapted for coöperation with the catches and projections in a manner to be described. In imparting movement to the drum I have provided a cable 23 and wrapped the same about the drum, one end of the cable being connected to a spring 24 which is in turn connected to the section 2 on the music rack. The opposite end of the cable is trained about an idler 25 and finally connected to the free end of a lever 26 pivotally mounted as at 27 to the front leg 3. A foot lever 28 is pivoted at its inner end to the lower end of the front leg 3 while a rod 29 serves to connect the foot lever 28 to the lever 26. When the lever 28 is depressed the lever 26 will also be depressed thus exerting a pull on the cable against the tension of the spring, and as the lever 28 is forced farther down the tension on the spring 24 increases, and because of this frictional engagement of the cable with the drum the latter is partially rotated. The catch 20 is arranged so as to engage one of the projections 18 and swing the arm about its pivot and against the cam edge 22 so as to force the projection against the cam edge and rotate the tube 9 until the catch 20 is released.

In order to control the movement of the drum I provide the lower edge with two oppositely disposed recesses 30 illustrated to advantage in Fig. 4. These recesses are engageable by a spring member 31 connected to the inner end of the bracket 8 as indicated by the numeral 32. It will now be apparent that after the drum 19 has been partially rotated and the catch 20 released as has been described, the spring 31 will automatically engage one of the notches 30 to prevent the reverse movement of the drum 19 after pressure has been relieved from the foot lever 28 which latter is returned to its former position by the spring 24. When the sheets of music are placed in the holders and all arranged on the right, the pivoted arm 33 on the support 5 should

be placed over the top sheet so as to hold the lower sheets in place while the top one is drawn from under it and turned.

The operation of my invention is as follows:—

Assuming that the device is in a position shown in Fig. 1 and that the leaf turning arms are arranged to the right side of the tube 1 which consequently places the projections 18 in uniformly spaced relation with each other, when the foot lever is depressed the tension is exerted on the spring 24 which in turn causes a frictional engagement of the cable with the drum 19 for partially rotating the drum. As is apparent, the catch 20 is arranged to engage the inner of the projections 18 and during the partial rotation of the drum one of the arms 16 is swung about its pivot and pressed against the cam surface 22 so as to partially rotate the tube 9 and bring the next projection in a position where it can be engaged by one of the catches. The first projection is forced against the cam edge until the catch is released whereupon the spring 31 will automatically engage one of the recesses 30 and prevent reverse rotation of the drum while the lever is being automatically reset by the spring 25. The lever can now be depressed which will cause the other catch 21 to engage the inner of the projections 18 and this operation is successively repeated until all of the leaf turning arms have been moved about their pivot. In resetting all of the arms it is only necessary to partially depress the foot lever and turn them to the right by handling each one at a time or all together.

Although I have shown and described the preferred embodiment of my invention I desire it to be understood that I am not to be limited to the exact details shown. However, I desire that great stress be laid upon the arrangement of the device that can be readily associated with various types of supports for turning sheets of music while the musician is playing his instrument. Attention is also directed to the peculiar co-operation existing between the drum with the catches and the leaf turning arms pivoted on the tube and having the projections engageable by the catches for the purpose set forth.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my invention and that various minor changes

in detail of construction, proportion and arrangement of the parts may be made within the scope of the appended claims and without sacrificing any of the advantages of my invention.

Having thus fully described my invention, what I claim as new and desire to secure by Letters Patent, is:—

1. A music leaf turner, including a rotatably mounted member, a plurality of leaf turning arms pivotally mounted in said member, a projection depending from and formed intermediate of the ends of each leaf turning arm, a drum adapted to be intermittently rotated and mounted adjacent said member, catches lying in the same transverse plane and projecting from the drum, said catches being adapted to successively engage the projections for swinging the leaf turning arms, a bracket having a cam surface engageable by each projection for partially rotating the rotatable member for placing the next projection in position to be turned, and means for intermittently rotating the drum.

2. A music leaf turner including a rotatably mounted member, a plurality of leaf turning arms pivotally connected to the member, a projection depending from each arm and each movable in the same plane, a rotatably mounted drum arranged eccentrically with respect to said member, catches extending in the same plane from the drum and spaced diametrically opposite for successively engaging the projections, means for intermittently rotating the drum so as to swing the arms, and means for preventing the movement of the drum while the actuating means is being reset.

3. A music leaf turner including a rotatably mounted member, a plurality of leaf turning arms, pivotally mounted on the member, a projection on each of the arms, a rotatably mounted drum arranged adjacent said member, catches on the diameter and extending from the drum for successively engaging the projections, a cable having an elastic end connected to a stationary object and having an intermediate portion arranged about the drum, and a pivotally mounted foot actuating lever in connection

with the other end of the cable for causing the cable to frictionally engage the drum to consequently actuate the leaf turning arms.

4. A music leaf turner including a main support, brackets extending therefrom, the lower of which is provided with a cam surface, a member rotatably mounted between the brackets, a plurality of leaf turning arms pivotally mounted on the member, a projection depending from each arm, said projection being formed by bending the arm in to approximately a V-shape, said arms being movable in the same path of travel, a rotatably mounted drum arranged eccentrically to the member, cams serving as catches extending from the drum, means for rotating the drum to cause one of the catches to engage one of the projections and swing the arm until the projection strikes the cam surface on the bracket for partially rotating the member, said latter movement releasing the catch and placing in an engaging position the next projection, and means for preventing the reverse rotation of the drum while the actuating means is being reset.

5. A music leaf turner comprising a rotatable member, a supporting bracket having said member rotatably mounted therein and having a cam surface thereon, a plurality of leaf turning arms pivotally mounted on said member to move in the same plane, a projection depending from each arm, a rotatable drum mounted eccentrically to the member, catches formed to lie in same plane and extending from the drum, and means for rotating the drum to cause one of the catches to engage one of the projections and swing the arm until the projection strikes the cam surface of the bracket, said member being thereby partially rotated for releasing the catch and for placing the next projection in position to be engaged by one of said catches.

In testimony whereof I affix my signature in presence of two witnesses.

TOM WILLIAMS.
